UNITED STATES PATENT OFFICE.

THOMAS SHIPLEY, OF YORK, PENNSYLVANIA.

ICE CAN.

Application filed May 17, 1924. Serial No. 714,152.

This invention relates to ice cans for use in raw water plants. In such plants it is usual to agitate the water in ice cans by means of a jet of air discharged into the water near the bottom of the can. The preferred location for the air jet is at or near the middle of the bottom of the can, but such a location of the air jet has heretofore involved difficulties because the air pipe must be led through the bottom joint flange of the can and it has proven impracticable prior to my invention to keep the joint tight around the air pipe hole.

One feature of the present invention resides in a special construction which precludes the possibility of such leakage.

Another feature of the invention resides in the means adapted to permit the ready removal and replacement of the air pipe. This is a matter of considerable difficulty in the case of so-called multiple can units in which a number of cans are rigidly mounted in a supporting frame.

It is now the practice to equip such units with a so-called air lateral pipe, extending the length of the unit, and with a plurality of branch pipes leading from the lateral to the cans, and housed in the narrow intervals between adjacent cans. The space between cans is so limited that it is difficult to provide a construction for the branch air pipes such that they may be removed and replaced without disturbing the air lateral, and without removing any of the cans from the frame.

This invention provides a construction of this type which also permits the air to be delivered through the bottom of the can.

A preferred embodiment of the invention is illustrated in the accompanying drawing, in which:

Fig. 1 is a fragmentary side elevation showing a portion of the supporting frame, and three of the cans supported thereby together with their air connections;

Fig. 2 is a section on the line 2—2 of Fig. 1;

Fig. 3 is an enlarged section through the bottom of a can on the line 3—3 of Fig. 2;

Fig. 4 is a plan view of the bottom connection shown in Fig. 3;

Fig. 5 is a section showing in detail the fitting preferably used to connect the air lateral with the branch pipes;

Fig. 6 is a fragmentary view similar to Fig. 3, showing a slightly modified construction.

The supporting framework of the can unit may be of any desired construction, and is not illustrated in detail. The side members of this frame are indicated at 11, and the supported cans are shown at 12. These cans are provided with reinforcing bands 13 at their mouths, as is usual.

Mounted on one side member 11 are a number of fittings 14 which support the air lateral pipe 15. The fittings 14 are best shown in detail in Fig. 5.

Each fitting 14 is bifurcated and straddles the side member 11, to which it is connected by a screw 16. It is provided with a port 17 which connects the air lateral 15 with a hollow manifold 18. Extending through the manifold 18 are two shouldered tubular members 19, one for each of the branch air pipes 20. The tubular members 19 are formed with a flow regulating constriction 21, leading to a port 22, which communicates with the interior of the manifold 18. The members 19 are threaded at their ends to receive cap nuts 23. The cap nuts 23 retain the members 19 in place and tight joints are afforded by means of gaskets 24.

The nuts 23 serve as guides for the heads 25 of clearing stems 26, which are movable through the constrictions 21 to clear the same. Each stem 26, adjacent the head 25, is provided with a flange 27 and gasket 28. A coil spring 29, surrounding the stem 26 and confined between the end of the tubular member 19 and the flange 27, serves to seat the gasket against the inner face of the nut 23, thus preventing leakage around the actuating head 25.

By pressing and releasing the head 25, the clearing stem 26 is moved longitudinally through the constriction 21, and serves to clear away any scale or other obstructions.

This construction provides a very convenient fitting for use in ice cans because the removal of the nuts 23 permits the withdrawal of the tubular members 19, thus free-

ing the pipes 20, without rotation of the branch pipe. In this detail it has some of the characteristics of a union fitting though specifically different therefrom.

5 The reason for connecting two pipes 20 to a single manifold 18 is to reduce the number of branch fittings required, since it is possible to locate two air pipes for two adjacent cans in the interval between these 10 two cans (see Fig. 1).

Referring particularly to Fig. 2, it will be observed that the air pipes 20 are given a gradual downward curvature, and then extend downward along the sides of the 15 cans to points near the bottoms thereof. The gradual curvature is to permit the pipe to yield to any differential expansion of the pipe relatively to the can. This feature is not specifically claimed herein as my co-pending application Ser. No. 714,153, filed 20 May 17, 1924 contains claims directed thereto. Near the bottom of the can (see Figs. 3 and 4) each pipe 20 bends sharply 25 inward toward its can, and passing through the bottom flange 30 of the can is connected to an angle fitting 31. This angle fitting 31 is threaded into a flanged plate 32 riveted to the bottom 33 of the can. The flanged plate 32 may be either on the inner or outer 30 side of the bottom plate 33, one arrangement being shown in Fig. 3, and the alternative arrangement in Fig. 6.

The connection between the tube 20 and the fitting 31 is a special type of union. 35 Fitting closely on the end of the tube 20 is a reversely beveled ring or sleeve 34, of relatively soft metal. This is received in a conical recess formed in the end of the fitting 31 and in a similar conical recess 40 formed on the inner face of the nut 35, which is threaded on the end of the fitting 31. The ring 34 is thus compressed around the end of the pipe 20 by screwing up the nut 35, but after the nut 35 has been removed it is possible to withdraw the ring 45 34 from the end of the pipe.

To prevent leakage where the pipe 20 passes through the joint flange 30 of the can, a reinforcing eyelet 36 is used. It is necessary to form the hole for the air pipe 50 after the flange 30 has been formed, and consequently after the bottom joint of the can has been made. After the hole is punched, the bottom flange is dipped in solder and then the eyelet 36 is set and sweated in place.

Finally, the flange with the eyelet in 55 place is again dipped in solder to insure an absolutely tight joint. The eyelet 36 reinforces the flange where it is weakened by the formation of the hole and the use of the eyelet produces a joint which is absolutely tight and will remain so.

60 The eyelet 36 is set near the bottom of the flange and this permits the withdrawal of

the air pipes 20. To remove a pipe, the nuts 29 and 35 are unscrewed. The clearing stems 26, with their springs, are removed with the nut 29, and the ring 34 and nut 35 are withdrawn from the end of the pipe. 70 It is then possible to withdraw the tubular member 19 from the manifold 18, swing the pipe 20 downward out of the space between the two cans, and finally withdraw the pipe from the eyelet 36. This pipe, or a similar 75 pipe, may then be put in place by reversing the operations just described.

The special type of union shown in Fig. 3 is important, because the removal of the ring 34 permits the removal of the nut 35. 80 It thus makes it possible to use an eyelet 36 only slightly larger than the pipe 20.

What is claimed is:

1. The combination of an ice can unit including a frame and a plurality of cans 85 fixed therein, said cans having projecting flanges at their bottoms; an air lateral pipe mounted on said can unit; a plurality of branch air pipes, one for each can, said pipes extending freely through holes formed 90 in the bottom flanges of corresponding cans and between adjacent cans; a releasable connection between one end of each branch pipe and the lateral pipe including a sleeve and a clamping nut therefor rotatable independently of the sleeve; and unions serving to connect the other ends of the branch pipes with the interiors of the cans, said branch pipes being capable of withdrawal 95 from said unions.

2. The combination of an ice can unit including a frame and a plurality of cans fixed therein, said cans having projecting joint flanges at their bottoms; an air lateral pipe mounted on said can unit and provided with manifolds adjacent intervals between cans; a plurality of branch air pipes, one for each can, arranged in pairs between the cans, and each extending freely through a hole in the joint flange of its corresponding 100 can; releasable connections between each pair of branch air pipes and a corresponding manifold, said connections including sleeves fixed to said branch pipes and clamping nuts 105 rotatable relatively thereto; and unions serving to connect the other ends of the branch pipes with the interiors of respective cans, said branch pipes being capable of withdrawal from said unions. 110

3. The combination of an ice can unit including a frame and a plurality of cans fixed therein, said cans having air pipe openings in their side walls leading to the intervals between adjacent cans; an air lateral pipe mounted on said can unit; a plurality of branch air pipes, one for each can, said pipes extending in the intervals between adjacent cans and entering said air pipe openings; a releasable connection between one end of each branch pipe and the 120. 125

lateral pipe, each connection including a sleeve and a clamping nut therein rotatable independently of the sleeve; and union connections serving to connect the other end of each branch pipe with the wall of the corresponding can.

4. The combination with a multiple can unit including a frame and cans mounted therein, of a ported fitting mounted on said frame; an air lateral pipe extending through said fitting and in communication with the port therein; a manifold carried by said fitting in communication with said port; and a plurality of air pipes for conducting air to respective cans, releasably connected with said manifold.

5. The combination with a multiple can unit including a frame and cans mounted therein, of a ported fitting mounted on said frame; an air lateral pipe extending through said fitting and in communication with the port therein; a manifold carried by said fitting and in communication with said port; a plurality of branch air pipes serving to conduct air to corresponding cans; and releasable connections between said branch air pipes and said manifold, each including a constriction, and a clearing stem mounted to move therein.

30 6. The combination with a multiple can unit including a frame and cans mounted therein, of a ported fitting mounted on said frame; an air lateral pipe extending through said fitting and in communication with the port therein; a manifold carried by said fitting and in communication with said port; a plurality of branch air pipes serving to conduct air to corresponding cans; and releasable connections between said branch air pipes and said manifold each including a constricted tubular member extending through said manifold and communicating therewith, a manually operable clearing stem for such constriction, a nut serving to retain said tubular member and to guide said stem, and a spring resisting movement of said stem.

7. A fitting comprising in combination a casing having inlet and discharge connections, and an interposed constriction; a clearing stem axially movable through said constriction and having an integral extension projecting through the wall of said casing; and a spring resisting movement of said stem.

50 8. A fitting comprising in combination a casing having an inlet, a discharge, and an interposed constriction; a clearing stem axially movable through said constriction and having an actuating member projecting through the wall of said casing; a spring urging said stem in one direction; and sealing means rendered effective by said spring and serving to prevent leakage around said

stem where the latter extends through said wall.

9. A fitting comprising in combination a casing having an inlet, a discharge, and an interposed constriction; a clearing stem axially movable through said constriction and having an actuating head projecting through the wall of said casing; a valve member carried by said stem and arranged to seat against the wall of said casing and seal the opening through which said actuating head projects; and a spring acting on said stem and serving to seat said valve.

10. A fitting comprising in combination a hollow member having aligned openings on its opposite sides; a tubular member mounted in said openings and extending through said casing, said member having a port connecting its interior with the interior of said casing; a manually operable clearing stem mounted for longitudinal movement in said tubular member; and a nut serving to retain said tubular member in place in said casing.

11. A fitting comprising in combination a hollow casing adapted for connection to a pipe or the like and having aligned openings in its opposite sides; a tubular member adapted for connection to a pipe or the like and mounted in said openings, said tubular member extending through said casing from side to side and having a port connecting the bore of the tubular member with the interior of said casing; a nut threaded on said tubular member, serving to retain said tubular member in said casing, said nut being formed with a guideway; a clearing stem mounted in said guideway projecting longitudinally into said tubular member and manually movable therein; a valve member formed on said stem and arranged to seal against leakage through said guideway; and a spring urging said stem in a valve closing direction.

12. A fitting comprising in combination a hollow casing adapted for connection to a pipe or the like and having aligned openings in its opposite sides; a shouldered tubular member having means for connecting it to a pipe or the like and extending through said casing from side to side by way of said openings, said member having a port communicating with the interior of said casing and a constriction interposed between said port and said pipe connecting means; a cap nut threaded on the end of said tubular member and retaining the same in position in said hollow casing, said nut being formed with a guideway aligned with the bore of said tubular member; a clearing stem projecting through said guideway and constriction; a valve member on said stem adapted to seat against said cap nut to preclude leakage through said guideway; and a spring urging said stem in a valve seating direction.

13. The combination with an ice can having a projecting lock seam consisting of a plurality of thicknesses of metal folded together and formed with an air pipe opening passing through said several thicknesses of metal, of a metal eyelet set in said opening and serving to clamp said thicknesses of

metal together; and an air conduit extending therethrough and connected with the interior of said can.

In testimony whereof I have signed my name to this specification.

THOMAS SHIPLEY.
